CHARGING DEVICE FOR INTERNAL COMBUSTION ENGINES

Marion Mallory, Detroit, Mich.

Application November 29, 1937, Serial No. 177,143

9 Claims. (Cl. 123—52)

This invention relates to the charging of internal combustion engines with a view to operating with greater efficiency, especially at intermediate speeds or part loads.

5 It is well known that a small engine operates much more efficiently than a larger engine under the same load, because the throttle is open wider and there is higher compression in the cylinders. For example, a car having a small engine may, 10 under average conditions, run with the throttle more than half way open when the speed is 30 miles per hour. The volume of the charge is great enough in proportion to the cylinder capacity to insure a high compression and the car 15 may run 30 miles on a gallon of gasoline. On the other hand, if the car is equipped with a large engine, the throttle will be open much less than half way at 30 miles per hour, the compression will be comparatively low and the car will run 20 perhaps less than 20 miles on a gallon of gasoline.

In all engines, and more especially in those having a carburetor and throttle to control the charge for different speeds, the efficiency drops rapidly as the throttle is moved toward closed 25 position. To satisfy the popular demand, however, it is necessary to provide an engine large enough to have sufficient reserve power to insure quick acceleration, high speed and good performance in climbing hills.

30 The object of this invention is to provide a charging device which operates in such a manner that all of the cylinders deliver full power when the throttle is nearly wide open, but when the throttle is only part way open, say less than half way, most of the power is delivered from one 35 half of the cylinders, while the other half receive a charge of air or very lean mixture containing barely enough fuel to ignite. Thus at intermediate speeds and part load, the operation is like that of a small engine. The throttle 40 is opened to a greater degree, consequently the compression is higher and the engine operates with greater efficiency. In idling, however, in order to insure smooth operation, all of the cylinders receive equal charges.

45 The invention is adapted to be used in connection with a multi-cylinder engine, and for the purpose of illustration, I have shown it as applied to a V type engine using two separate intake manifolds and what is known as a double carburetor. In all engines using two manifolds, each bank of cylinders is balanced; that is, the cylinders of each bank fire at even intervals, so that if one bank is cut out, the other bank is still 50 balanced.

The construction of the invention will be more particularly described in connection with the accompanying drawing, in which—

Fig. 1 is a vertical transverse section through the engine intake and the charging means therefor. 5

Fig. 2 is a fragmentary section taken on the line 2—2 of Fig. 1.

As shown in the drawing, the manifold 5 is adapted to supply a charge to one bank of cylinders and the manifold 6 is adapted to supply a charge to the other bank. The mixing chamber 7 leading to the manifold 5 has an air inlet 8, venturi 9, fuel inlet nozzle 10 and throttle valve 11. The mixing chamber 12 leading to 10 the manifold 6 has an air inlet 13, venturi 14, fuel inlet nozzle 15 and throttle valve 16. The throttle valves 11 and 16 are mounted on a common shaft 17, which is provided with the usual crank 18 adapted to be operated from the ac- 20 celerator pedal.

A fuel line 19 leads from the carburetor bowl 20 to the nozzle 10 and another fuel line 21 leads from the bowl to the nozzle 15. A line 22 leads to the idle jets for both chambers 7 and 12. Each 25 idle jet has an orifice 23 which is below the throttle valve and a second orifice 24 which is just above the throttle valve when the latter is closed. When the throttle is closed, the fuel line 21 to the nozzle 15 is closed by a needle valve 30 25, which is slidably mounted in a sleeve 26. This needle valve is secured to a stud 27, which extends through a slot 28 formed in the upper end of a link 29, the lower end of the link being pivotally connected to the end of a crank 30 secured to 35 the throttle valve shaft 17. A lug 31 on the needle valve stem is connected by a spring 32 to a lug 33 on the side of the mixing chamber housing, which holds the needle valve on its seat until, as the throttle is opened, the stud 27 is engaged by 40 the lower end of the slot 28, the needle valve being then lifted against the resistance of the spring.

In the operation of the invention, enough fuel will be supplied through the holes 23 to idle the 45 engine when the throttle is closed. As soon as the throttle is opened a little, fuel is also fed through the holes 24. The idle line 22 has an air bleed, as indicated at 34, so that considerable suction is required to draw fuel from the holes 23 50 or 24. Upon further opening of the throttle, as the vacuum in the vicinity of the jets drops to 12" or 14" of mercury, these jets cease to flow and most of the power charge is supplied through the nozzle 10.

- As the lower end of the slot 28 engages the stud 27, the needle valve or metering pin 25 is lifted from its seat and sufficient fuel flows from the nozzle 15 to form a lean but ignitable mixture, 5 while most of the power is derived from the bank of cylinders which are charged from the nozzle 10. Thus for intermediate power demands, the throttle is opened much wider, the compression is much higher and the engine operates much 10 more efficiently than if a full charge were supplied to both banks of cylinders. As a matter of fact, as the throttle is progressively opened and fuel ceases to flow from the holes 23 and 24, a power charge will be supplied to one bank of 15 cylinders through the nozzle 10, while no fuel at all is supplied to the other bank of cylinders until the lower end of the slot 28 engages and lifts the pin 25 and allows fuel to flow from the nozzle 15.
- 20 When full power is demanded, with the throttle wide open or nearly so, the needle valve or metering pin 25 is lifted high enough so that it offers no obstruction to the flow of fuel from the nozzle 15.
- 25 From the foregoing description, it will be seen that the invention permits the realization of all the advantages of a multi-cylinder high-powered engine in idling or in full power operation, and permits operation at intermediate speeds and at 30 light loads with the economy of a smaller engine. Obviously the invention may be used with an engine having any number of cylinders, either straight or V type. The length of the slot 28 may be determined so that it will begin to lift 35 the metering pin 25 at any desired point in the opening movement of the throttle, the pin being so tapered that, at wide open throttle, the flow of fuel from the nozzle 15 will be the same as that from the nozzle 10.
- 40 I claim as my invention:
1. In a charging device for multi-cylinder engines, two mixing chambers adapted to be connected to two different sets of cylinders, a throttling device including valves for the respective chambers, means for supplying like fuel charges to the respective chambers when the throttling device is in idling or wide open position and for supplying more fuel to one chamber than to the other when the throttling device is in an intermediate position.
  2. In a charging device for multi-cylinder engines, two mixing chambers adapted to be connected to two different sets of cylinders, a throttling device including valves for the respective chambers, fuel jets of like capacity for supplying fuel to the respective chambers for idling and for power demand, and means for cutting down the flow through one of the power supply jets only when the throttling device is within a predetermined range between idling and full open position.
  3. In a charging device for multi-cylinder engines, two mixing chambers adapted to be connected to two different sets of cylinders, a throttling device including valves for the respective chambers, fuel jets of like capacity to charge both chambers for idling, ducts of like capacity for supplying fuel charges to the two chambers for power, and throttle controlled means for cutting down the flow through one of said power supply ducts only when the throttling device is within a predetermined range between idling and full open position.

4. In a fuel charging device, two intake manifolds, each with a separate mixing chamber and a throttle valve, fuel ducts of the same capacity for supplying fuel for power to the respective chambers, and means operated in conjunction with the throttle valves to cut down the flow through one of said ducts only throughout a predetermined movement of the throttle valves.

5. In a fuel charging device, two intake manifolds, each with a separate mixing chamber and a throttle valve, a common shaft to which the throttle valves are secured, fuel ducts of the same capacity for supplying fuel to the respective chambers, a metering pin associated with one of said fuel ducts only, and means operable from the throttle valve shaft to control said metering pin to restrict the flow of fuel through the duct associated therewith for predetermined throttle positions.

6. In a fuel charging device, two intake manifolds, each with a separate mixing chamber and a throttle valve, a common shaft to which the throttle valves are secured, like means for supplying idling charges to the two manifolds when the throttle valves are closed or nearly closed, fuel ducts of like capacity for supplying fuel to the respective chambers as the throttle valves are opened wider, and means operable in conjunction with the throttle valve shaft to delay the full capacity operation of one of said ducts until the throttle valves are opened to a predetermined position.

7. In a fuel charging device, two intake manifolds, each with a separate mixing chamber and a throttle valve, a common shaft to which the throttle valves are secured, like means for supplying idling charges to the two manifolds when the throttle valves are closed or nearly closed, fuel ducts of like capacity for supplying fuel to the respective chambers as the throttle valves are opened wider, a metering pin associated with one of said fuel ducts only, and means operable in conjunction with the throttle valve shaft to control said metering pin to restrict the flow through the duct associated therewith, thereby delaying the full capacity operation thereof, until the throttle valves are opened to a predetermined position.

8. In a charging device for multi-cylinder engines, two mixing chambers adapted to be connected to two different sets of cylinders, a throttling device including valves for the respective chambers, means for supplying like fuel charges to the respective chambers when the throttling device is in idling or wide open position, and means to preclude any fuel supply to one of said chambers throughout an intermediate throttle range.

9. In a charging device for multi-cylinder engines, two intake passages adapted to be connected to two different sets of engine cylinders, a source of fuel supply leading to the two intake passages, throttling means for said passages operable in idling, wide open, and intermediate positions, means to supply equal fuel mixture charges to both of said passages when the throttling means is wide open, and means to cut off the fuel charge to one of said passages when the throttling means is in an intermediate position.

MARION MALLORY.
